UNITED STATES PATENT OFFICE.

FRANK SCHUSTER, OF ERIE, PENNSYLVANIA.

ENVELOPE.

Application filed March 31, 1923. Serial No. 629,114.

To all whom it may concern:

Be it known that I, FRANK SCHUSTER, a citizen of the United States of America, residing at Erie, in the county of Erie and 5 State of Pennsylvania, have invented certain new and useful Improvements in Envelopes, of which the following is a specification.

This invention relates to certain new and useful improvements in envelopes and has 10 for its primary object to provide a series of interconnected flaps and tongues carried by the blank of the envelope for securely retaining the same in a sealed condition to prevent unauthorized access thereto, the envelope 15 being sealed and folded in a manner whereby detection of unauthorized tampering therewith may be readily noted.

With the above and other objects in view as the nature of the invention is better understood, the same consists of the novel 20 form, combination and arrangement of parts hereinafter more fully described, shown in the accompanying drawing and claimed.

25 In the drawing, wherein like reference characters designate corresponding parts throughout the several views,

Figure 1 is a plan view of the envelope blank in its unfolded position, showing the 30 several blank portions, sealing flaps, tongues and gummed portions,

Figure 2 is a plan view of the envelope in its partially folded position,

Figure 3 is a fragmentary plan view of 35 one of the end flaps and sealing tongues carried thereby, and

Figure 4 is a bottom plan view of the envelope in its completely folded and sealed position.

40 Referring more in detail to the accompanying drawing, there is illustrated an envelope formed from a blank embodying a central section 1, end sections 2 and 3 and upper and lower flap sections 4 and 5, all 45 of the sections being preferably of rectangular formation as illustrated in plan view in Fig. 1, the end flap sections 2 and 3 being foldable upon the lines 6 while the upper and lower flap sections 4 and 5 are foldable 50 upon the lines 7 and 8. A slot 9 is provided intermediate the ends of the fold line 7, and a slot 10 is formed intermediate the ends of the fold line 8, the lower flap section 5 being provided with spaced splits 11 alined 55 with the slot 10 as illustrated in Fig. 1. The end flap section 2 is also provided with

spaced parallel splits 12 for purposes presently to appear.

The lower corner edge of the flap section 2 carries a gummed tab 13 foldable upon 60 the line 14, while the end flap section 3 at its upper outer edge carries a gummed tab 15 foldable upon the line 16. A gummed tab 17 is carried by the outer edge of the end flap 3 and is connected thereto by the reduced neck 18, the opposite sides of the gummed tab 17 being foldable upon the 65 lines 19.

The outer edge of the upper flap section 4 is serrated as at 20 and gummed, a 70 gummed tab 21 and reduced connecting neck portion 22 being carried intermediate the ends of the upper flap section 4 with the opposite side edges of the tab 21 foldable upon the lines 23.

75 In folding the envelope blank into the sealed condition illustrated in Fig. 4, the end flap 2 is first folded upon the line 6 to overlie the central section 1 and the gummed tab 13 passed through the slot 10 with the 80

gummed face thereof adhesively secured to the outer face of the central section 1, the gummed tab 13 being folded upon the line 14.

The end flap section 3 is then folded upon the line 6 and the gummed tab 15 inserted through the slot 9 and folded upon the line 16 to be adhesively secured to the outer face of the central section 1. To pass the tab 13 through the spaced parallel slits 12, the opposite sides of the tab 17 are folded 85 upon the lines 19 to reduce the tab 17 to the size of the connecting neck portion 18,

the tab when passed through the slits 12 as shown in Fig. 2 having the opposite sides thereof unfolded and adhesively secured to 90 the outer face of the end section 2 as shown in Fig. 2. The lower flap section 5 is then folded upon the line 8 to overlie the end flap sections 2 and 3, and the upper flap section 4 is folded upon the line 7 to overlie 95

the adjacent edge of the lower flap section 5, the opposite ends of the gummed tab 21 being folded upon the lines 23 for passage through the spaced slit 11 as described in 100 connection with the securing of the flap 17

105 and finally adhesively secured to the outer face of the lower flap 5, the serrated gummed edge 20 of the flap section 4 also being adhesively secured to the lower flap section.

With the envelope so folded, it will be impossible to tamper therewith in an attempt 110 to obtain access to the contents of the en-

velope without detection thereof, this type of envelope providing an unusually safe container for written matter to be carried through the mail.

5 While there is herein shown and described the preferred embodiment of the present invention, it is nevertheless to be understood that minor changes may be made therein without departing from the spirit and scope 10 of the invention as claimed.

What is claimed as new is:—

1. In an envelope of the type described, a blank embodying a rectangular center section and a rectangular flap carried by each 15 edge thereof and foldable upon the marginal lines of the center section, said center section having a slot formed at opposite marginal portions thereof, one end and side flap having spaced parallel slits formed therein, 20 a gummed tab carried by the slotted end flap adapted to be passed through one of said slots, a tab carried by the other end flap adapted to be passed through the other slot, a second tab carried by the last named flap

adapted to be passed through the slits in the 25 end flap, and a gummed tab carried by one side flap adapted to be passed through the slits in the other side flap.

2. In an envelope of the type described, a blank embodying a rectangular center section and a rectangular flap carried by each 30 edge thereof and foldable upon the marginal lines of the center section, said center section having a slot formed at opposite marginal portions thereof, one end and side 35 flap having spaced parallel slits formed therein, a gummed tab carried by the slotted end flap adapted to be passed through one of said slots, a tab carried by the other end flap adapted to be passed through the other 40 slot, a second tab carried by the last named flap adapted to be passed through the slits in the end flap, a gummed tab carried by one side flap adapted to be passed through the slits 45 in the other side flap, and a gummed serrated edge on the tab carrying side flap.

In testimony whereof I affix my signature.

FRANK SCHUSTER.
